UNITED STATES PATENT OFFICE

WILLIAM H. KLOCKE, OF WOODHAVEN, NEW YORK, ASSIGNOR TO THE CLEVELAND GRAPHITE BRONZE COMPANY, OF CLEVELAND, OHIO, A CORPORATION OF OHIO

METHOD OF MAKING BEARINGS

Application filed December 28, 1928. Serial No. 328,965.

The present invention, relating, as indicated, to a bearing and method of making the same is particularly directed to a means for preventing leakage during the lining of a cylindrical shell with molten bearing metal where the shell is formed either from a single strip of flat stock or from two or more strips of flat stock bent into segments of a cylinder.

10 To the accomplishment of the foregoing and related ends, said invention, then, consists of the means and steps hereinafter fully described and particularly pointed out in the claims; the annexed drawings and the following description setting forth in detail certain means and one mode of carrying out the invention, such disclosed means and mode illustrating, however, but one of various ways in which the principle of the invention may 15 be used.

In said annexed drawings:—

Fig. 1 is a side elevation partially in section of an apparatus adapted for the lining of shells of the character described; Fig. 2 is a 25 transverse sectional view showing two half shells mounted together to form a single shell, against which bearing metal is to be cast internally; and Figs. 3 and 4 are similar partial views showing modifications of the 30 joint shown in Fig. 2.

In the manufacture of lined bearings the shell proper of the bearing may be formed either of tubular stock, of a single strip of flat stock formed into a cylinder, or of two or 35 more strips of flat stock formed into segments of a cylinder and then assembled to provide a complete cylinder. In the use of tubular stock there is of course no possibility of leakage when bearing metal is subsequently cast even under heavy pressure against the 40 interior of the shell. In the case of shells formed from a single piece of flat stock it is necessary to provide a fluid-tight joint in order to prevent leakage during the casting 45 operation, and while by suitable forming methods it is possible to secure such a joint it is sometimes more convenient to provide against leakage by certain subsequent precautions. In the case of assembling shells 50 consisting of two or more segments of a cylinder

it is of course always necessary to provide some additional means for securing either pressure across the joints or barriers at these joints to prevent leakage. The present invention relates to this last-named means 55 for providing tight joints in such types of shells during the lining operation.

In Fig. 1 there is shown a shell 1 provided with one or more joints 2, the shell being mounted between conical chucks 3 and 4 60 which it is understood are capable of movement toward each other to clamp the shell concentrically and tightly therebetween. One of the two chucks is hollow and is provided with a pouring spout 5 extending into the interior of the shell 1, through which molten bearing metal, such as babbitt, may be introduced into the shell. During the introduction and cooling of the bearing metal the chucks and shell are rapidly rotated and the bearing metal is thus carried around the interior of the shell and is applied evenly and concentrically thereto.

In Fig. 2 I have shown two half shells 10 and 11 assembled to form a complete shell, 75 the joints between the ends of the two shells being closed by means of barriers in the form of soft wires 12 extending from end to end of the two shells. The two half shells when thus assembled are placed in the chucks 3 and 4, the latter are tightened to hold the shells together, and this tightening action presses the ends of the shells against the wires and produces a snug tight engagement between the wires and the end walls of the shells. 80 When molten bearing metal is subsequently poured into this shell and is caused to flow into the openings between the ends it contacts of course with the wires 12 and as the latter are pressed into any irregularities with the ends of the two shells it is impossible for the molten metal to leak past the wires and to be thrown from the rotating shells.

An even more effective joint is shown in Fig. 3, in which the ends of the shells or shell are provided with notches 13 in which a wire 14 is laid, the wire extending partly into each of the ends of the shell and making it necessary for any molten metal to pass 95 100

completely around the wire, as well as through the engaging ends of the shell before it can escape.

Another type of joint is shown in Fig. 4, in which recesses 15 and 16 are formed in the outer end of each shell, the recesses stopping short of the inner circumference and providing a space upon assembly of the shells into which the wire 17 may be snugly fitted.

10 In this type of joint molten metal must first pass between the contacting edges of the shells and then around the wire before it can escape. All of the types of joint illustrated have been found effective under the ordinary 15 commercial casting conditions and one or the other may be employed, depending upon, first, the cost, and second, the casting pressure which it is necessary to resist.

It will also be understood that the type of 20 joint selected will depend to some extent upon whether the cylindrical shell consists of a single strip of metal with a single joint, or is formed of two half shells. In either case the ends of the shell or of the half shells may 25 be formed as indicated in Figs. 3 and 4 either before the strips are formed, but if either of these joints be employed in a shell formed of two half shells the end faces may be prepared after the formation of the strips into their 30 semi-cylindrical form.

Other forms may be employed embodying the features of my invention instead of the one here explained, change being made in the form or construction, provided the elements stated by any of the following claims 35 or the equivalent of such stated elements be employed, whether produced by my preferred method or by others embodying steps equivalent to those stated in the following claims.

40 I therefore particularly point out and distinctly claim as my invention:—

1. In a method of making lined bearings, the steps which consist in forming two semi-cylindrical shells, assembling the same into 45 a cylinder with intermediate elements engaged between the adjacent ends of said half shells and snugly clamped therebetween, rotating the assembled cylinder while maintaining a pressure across the adjacent ends 50 of the half cylinders and introducing molten bearing metal into the interior of said shell.

2. In a method of making lined bearings, the steps which consist in forming two semi-cylindrical shells, assembling the same into 55 a cylindrical shell with interposed wires extending longitudinally between the adjacent ends of the half shells, clamping said two half shells together, and casting bearing metal under pressure against the inner surface of said shells.

Signed by me, this 22nd day of Dec., 1928.

WILLIAM H. KLOCKE.
